UNITED STATES PATENT OFFICE

JOHN F. KIRGAN, OF EASTON, PENNSYLVANIA, ASSIGNOR TO INGERSOLL-RAND COMPANY, OF JERSEY CITY, NEW JERSEY, A CORPORATION OF NEW JERSEY

STEAM CONDENSER

Application filed May 21, 1927. Serial No. 193,151.

This invention relates to steam condensers, and more particularly to the surface or tubular type.

It is an object of this invention to enable 5 a maximum quantity of steam to be condensed for a given tube surface and cooling water temperature. More specifically, it is an object of this invention to arrange the tubes in such a manner that the flow of steam 10 around the tubes is choked at the warmer end of the condenser and the greater part of the steam directed toward the cooler end in which the condensing capacity is greater.

These and other objects of the invention 15 will become apparent by referring to the following description of the drawings, in which—

Figure 1 is a horizontal section of a condenser constructed in accordance with the 20 invention and taken along the line 1—1 of Figure 3 looking in the direction of the arrows,

Figure 2 is a vertical section through the condenser taken along the line 2—2 of Figure 1 looking in the direction of the arrows,

Figure 3 is a cross section of the condenser at the cooler end taken along the line 3—3 of Figure 1 looking in the direction of the arrows, and

Figure 4 is a cross section of the condenser at the warmer end taken along the line 4—4 and looking in the direction of the arrows.

Referring to the drawings, the condenser comprises a shell or casing A having a steam

35 inlet B preferably at the top end and outlet C for air and non-condensable gases which in this instance is also used to conduct condensate from the shell. Suitable evacuating apparatus (not shown) is adapted to be connected to the outlet C to maintain a suitable

40 vacuum within the casing A. At opposite ends of the casing A are provided an inlet water box D and an outlet water box E which are connected to each other through the cas-

45 ing A by tubes arranged in rows F and G alternating as described hereinafter. The tubes in the rows or layers F and G are suitably sealed at their ends in tube sheets H at the water boxes D and E.

50 In condensers of the general type above

referred to, the tendency of the steam is to penetrate less deeply at the cooler end of the condenser near the inlet water box D than at the warmer end adjacent the outlet water box E. This is due to the lower temperature of the water at the cooler end of the condenser and its rise in temperature as it approaches the water outlet box E. The conditions within the condenser are more fully explained and referred to in United States patent to P. A. Bancel No. 1,550,332, granted August 18, 1925.

In accordance with this invention, greater depth of penetration in the cooler section of the condenser is secured by arranging the tubes at the cooler end of the condenser to provide steam lanes and at the warmer end providing a staggered tube arrangement as shown in Figure 4. To this end certain layers of tubes G are moved over into vertical alignment with the tubes in the layers F as shown in Figure 3. Since the tubes in the rows F and G are straight, or substantially so, the lanes formed at the cooler end of the condenser are gradually closed as the tubes approach the warmer end of the condenser as shown in Figure 1 forming a graduated opening gradually obstructing the steam.

To operate the condenser at its best efficiency the evacuating apparatus (not shown) connected at the air outlet C is preferably caused to draw a vacuum at the bottom of the casing A to cause steam to be drawn through the warmer end of the condenser down to the last row of tubes. Since the obstruction to the flow of steam is less at the cooler end than at the warmer end, steam will be drawn also to the lowest row of tubes in the cooler end notwithstanding the greater steam condensing capacity in that end.

It is evident that the pressure drop from the steam inlet B to the air outlet C must be equal throughout the length of the condenser. The pressure drop is dependent on two factors, the velocity or the quantity and the friction loss of steam flowing through a section. In order to equalize the pressure drops in the cooler and warmer ends, the velocity and quantity of steam in the cooler

end is increased and the obstruction to the passage of the steam is decreased.

Thus by the above construction are accomplished among others the objects hereinbefore referred to.

5 I claim:

1. A surface condenser comprising a casing having a steam inlet and an outlet for air and non-condensable gases, an inlet water box for said casing and an outlet water box for said casing, and rows of tubes connecting said boxes arranged in substantially parallel planes perpendicular to the path of steam flow, said tubes being arranged in parallel vertical rows at the end of the condenser adjacent the inlet water box, and alternate tubes in a vertical direction at the other end of the condenser being displaced side-wise with respect to the remaining tubes to 10 provide a staggered arrangement.

2. A surface condenser comprising a casing having a steam inlet and an outlet for air and non-condensable gases, an inlet water box and an outlet water box arranged as opposite ends of the condenser, and tubes interposed between the steam inlet and the air outlet and connected with said water boxes, said tubes being bunched at the ends adjacent the inlet water box to provide steam lanes 15 to facilitate the passage of steam therethrough.

3. A surface condenser comprising a casing having a steam inlet and an outlet for air and non-condensable gases, an inlet water box 20 and an outlet water box at opposite ends of said condenser, and tubes arranged transversely to the path of steam flow and connecting with said water boxes, said tubes being arranged in parallel layers lying in planes substantially perpendicular to the path of steam flow, the tubes being in staggered relation adjacent the water outlet box and in 25 rectangular arrangement to each other in the various layers adjacent the water inlet box the tubes in alternate layers being straight and substantially parallel to the casing, and the tubes in successive layers being non-parallel to the casing.

40 In testimony whereof I have signed this specification.

JOHN F. KIRGAN.

CERTIFICATE OF CORRECTION.

Patent No. 1,749,141.

Granted March 4, 1930, to

JOHN F. KIRGAN.

It is hereby certified that error appears in the printed specification of the above numbered patent requiring correction as follows: Page 2, lines 43 and 44, claim 3, strike out the words "in the various layers"; and that the said Letters Patent should be read with this correction therein that the same may conform to the record of the case in the Patent Office.

Signed and sealed this 25th day of March, A. D. 1930.

(Seal)

M. J. Moore,
Acting Commissioner of Patents.
